UNITED STATES PATENT OFFICE.

WILLIAM F. ZIMMERMANN, OF NEWARK, NEW JERSEY, ASSIGNOR TO GOULD & EBERHARDT, OF NEWARK, NEW JERSEY, A CORPORATION OF NEW JERSEY.

PROCESS FOR CUTTING HELICAL GEAR-WHEELS.

1,036,948.

Specification of Letters Patent. Patented Aug. 27, 1912.

Original application filed October 24, 1907, Serial No. 399,033. Divided and this application filed November 1, 1911. Serial No. 657,970.

To all whom it may concern:

Be it known that I, WILLIAM F. ZIMMERMANN, a citizen of the United States, and a resident of Newark, in the county of Essex and State of New Jersey, have invented certain new and useful Improvements in Processes for Cutting Helical Gear-Wheels, and do hereby declare the following specification, taken in connection with the drawings forming part of the same, to be a full, clear, concise, and exact description of the principle of the invention and the best mode contemplated to apply said principle, so as to distinguish it from other inventions and to enable any person skilled in the art to which it appertains or with which it is most nearly connected to make, construct, and use the same.

The invention relates primarily to a method of generating teeth in helical gear wheels without imparting a differential motion to either the blank to be cut or to the cutter therefor, and more particularly to a process employing a helical or hob cutter.

This invention is applicable to the apparatus shown and described in a co-pending application of the applicant, filed October 24th, 1907, Serial No. 399,033, of which case this invention is a division.

The object of this invention is to provide a process of cutting helical gear wheels with a helical cutter by imparting a single resultant motion to said cutter and blank spindle in contradistinction to a differential motion, and of feeding said cutter parallel to the axis of, and relative to the rotations of said blank spindle, to produce helical teeth having their directrix coinciding with the axis of said blank spindle. The rotational and feeding motions of the cutter and the rotational motion of the blank are in accordance with a mathematical formula from which the different relative ratios may be obtained for the various helical gear wheels to be cut.

The formula hereinafter deduced is based on the aforesaid feeding motion being relative to the rotations of the blank spindle.

The annexed drawings and description thereof set forth in detail, certain mechanism embodying means constituting, however, but one of the various mechanical forms in which the principle of the invention may be used.

The novelty of the invention will be read-

ily understood from the drawings, which show a construction for practising the invention in its preferred form, and from the following description thereof, and is more particularly pointed out and distinctly claimed in the claims annexed to said description.

In the drawings Figure 1 is a side view of the apparatus embodying the features necessary to practise this invention. Fig. 2 is a section through a constant driving train taken at X X₁ of Fig. 1. Fig. 3 is a partial rear elevation partly in section to illustrate the driving mechanism.

In order to fully understand the invention, the formula for determining the relative ratios will be deduced after the following notation:

P^{NC} =normal circular pitch of helical gear to be cut or the shortest distance between any two consecutive teeth and is measured on the normal to the helices and determines the size of the cutter to be used.

P^{ND} =normal diametral pitch of the helical gear and cutter.

P^c =circular pitch and is measured at right angles to the axis of the gear.

P^L =linear pitch measured parallel to the axis of the gear.

N =number of teeth in the gear.

D =pitch diameter of the gear.

D^o =outside diameter of the gear.

a =addendum.

X =angle of the helices with the axis of the gear.

L =lead of the helices or the advance in one turn.

The following formulæ are ordinarily used to determine the various parts of a helical gear when the usual known quantities are given, to wit: P^{NC} , N and X :

$$P^{NC} = \frac{\pi}{P^{ND}} \cdot P^c = \frac{P^{NC}}{\cos. X} \cdot P^L = \frac{P^{NC}}{\sin. X}$$

$$D = \frac{N}{P^{ND} \cos. X} = \frac{N P^{NC}}{\pi \cos. X} \cdot D^o = D + 2a \quad 100$$

$$a = \frac{P^{NC}}{\pi} = \frac{1}{P^{ND}}$$

$$L = \frac{N P^{NC}}{\sin. X} = \frac{N P^c}{\tan. X} = \frac{N \pi}{P^{ND} \sin. X} \quad 105$$

In cutting a helical gear upon any automatic helical gear cutting machine with a

helical cutter, it is always necessary to rotate the blank in unison with the helical cutter at a speed depending upon the number of teeth to be cut, while at the same time, the cutter is advanced across the face of the blank in what results in a helical path upon the peripheral face of the blank, passing around the axis of the blank, such path being due in other machines to differential gears inserted in the cutter drive or indexing mechanism. This invention produces such a helical path by adding or subtracting a small increment to or from the rotary speed of the blank or cutter, according to 15 the style of gear to be cut, such increment depending on the relation of the forward motion of the helical cutter to the rotation of the blank spindle.

To index in a machine, as will be described hereinafter, the formula for the 20 number of teeth would be $\frac{K}{N}$ where K represents a constant depending upon the relative 25 ratios of rotation of the work spindle to that of the helical cutter, and N represents the number of teeth to be cut. The lead L of the helices as shown above equals

$$30 \quad \frac{NP^{NC}}{\sin. X} = \frac{NP^c}{\tan. X} = \frac{N\pi}{P^{ND} \sin. X}$$

The formula which the present invention is based on is as follows:—To index for any 35 number of teeth for spur gears, the formula is $\frac{K}{N}$ in which K is a constant depending upon the relative rotational ratios of the work spindle and the helical cutter; N

$$\frac{V}{K'} \times \frac{KK' \sin. X}{K'N^2P^{NC} \mp NV \sin. X} = \frac{KV \sin. X}{N(K'NP^{NC} \mp V \sin. X)}$$

which represents the amount to be added or subtracted from the index formula $\frac{K}{N}$ to obtain the proper helix of the spiral or chevron gear to be cut.

The above increment is added when using

$$\frac{K}{N} \mp \frac{KV \sin. X}{N(K'NP^{NC} \mp V \sin. X)} = \frac{KK'P^{NC}}{K'NP^{NC} \mp V \sin. X} = R$$

The proof of the above calculation can at 40 all times be tested by the following proof formula which is composed of the number of revolutions the blank spindle made for indexing, subtracted from the entire revolutions made by the said blank spindle, the result will equal ∓ 1 which is the extra revolution for the helix, the signs depending upon the above formula. This can be shown in the following way: Let

$$100 \quad \frac{K'NP^{NC}}{V \sin. X}$$

equals the number of teeth to be cut. Letting

$$\frac{NP^{NC}}{\sin. X}$$

equal the formula for the lead in which P^{NC} equals the normal circular pitch of the spiral gear and X the angle of the gears with its axis, and $\frac{V}{K'}$ represents the relative rota-

tional ratio of the feed train of gearing with the work spindle, in which V is a variable 50 depending upon the ratio of the feed change gears and K' the relative ratio of the constant feed gearing with the work spindle. Then since the feed is controlled from the revolutions of the work spindle, we must 55 subtract or add

$$\frac{V}{K'} \text{ from } \frac{NP^{NC}}{\sin. X}$$

which equals

$$\frac{K'NP^{NC} \mp V \sin. X}{K' \sin. X}$$

dividing the result by the indexing formula $\frac{K}{N}$, we have:

$$\frac{K'NP^{NC} \mp V \sin. X}{K' \sin. X} \times \frac{N}{K} = \frac{K'N^2P^{NC} \mp NV \sin. X}{K' \sin. X}$$

which eliminates the tooth factor. Then dividing the feed ratio formula

$$\frac{V}{K'} \text{ by } \frac{K'N^2P^{NC} \mp NV \sin. X}{KK' \sin. X}$$

which is

a right-hand cutter to cut a right-hand gear or a left-hand cutter to cut a left-hand gear. It is subtracted when using a right-hand cutter to cut a left-hand gear, and when cutting a right-hand gear with a left-hand cutter. Thus the formula becomes:

$$\frac{KK'P^{NC}}{RV \sin. X} = R$$

equal the total number of revolutions of the blank spindle and

$$\frac{KK'P^{NC}}{RV \sin. X} = R$$

equal the revolutions for indexing; subtracting one from the other we will have:

$$\frac{K'NP^{NC}}{V \sin. X} - \frac{KK'P^{NC}}{RV \sin. X} = \frac{K'P^{NC}(RN - K)}{RV \sin. X} = \mp 1$$

To illustrate the above formula, the following example has been calculated: substituting in the formula for K a constant value

60, and K' a constant value 16, the formula becomes:

$$X = 30^\circ \quad \frac{960P^{NC}}{16N P^{NC} - V \sin X}$$

Taking a gear having

$$40T, 5/8P^{NC}, V = \frac{1}{1}$$

10 and substituting the known values, we have:

$$\frac{960 \times 5/8}{16 \times 40 \times 5/8 - (1/1 \times 1/2)} = \frac{1200}{799} = R$$

15 Applying the proof formula, we obtain

$$\frac{16 \times 5/8 (1200/799 \times 40 - 60)}{1200/799 \times 1/1 \times 1/2} = +1$$

20 the assumption being that the gear was right-hand, using a right-hand cutter, or left-hand using a left-hand cutter, and that the cutter was single threaded, if the same had a multiple number of threads proper correction can be made by a corresponding 25 reduction in the factor N.

Proceeding now with the detailed description of the mechanism to practise the invention, the main frame 1 is provided with a stanchion 2 at one end thereof, preferably 30 cast integral therewith. A work slide 3 is adjustably mounted upon the horizontal portion of the main frame 1, and is provided with a revoluble work spindle 4 therein, in which the work arbor 5 is secured, 35 whereby the gear blank 6 may be centered and secured to the spindle 4 in the usual way. A worm or index wheel 7 is secured to the lower end of the work spindle 4 and rotated by the worm 8 in engagement therewith. The index worm 8 is mounted in the bearings 9 of the work slide 3, and is provided with a gear 10 secured to one end thereof to engage with a gear 11, which is slidably keyed to the index shaft 12. The 40 index shaft 12 extends along the side of the main frame and is mounted in bearings at either end thereof and connected to the index driving shaft 13 by means of a compound train of change wheels which are arranged 45 in accordance with the formula hereinbefore described. The change gear 14 secured to the index shaft 12 meshes with a second change gear 15 rotatably mounted upon the stud 16 carried by the arm 17. A third change 50 gear 18, also rotatably mounted on said stud 16 is arranged to rotate in unison with said second change gear 15 and meshes with the change gear 19 secured to and rotatable with the index driving shaft 13. The stud 16 is 55 slidably arranged in the arm 17 to accommodate various diameter change gears and is secured thereto by the bolt 20. The arm 17 carrying the stud 16, is pivotally mounted upon the index shaft 12, and is secured in

the various positions to the index shaft bearing 21 by the bolts 22. The index shaft 12 has also secured thereto and rotatable therewith, a feed driving gear 23 which meshes with one of the two tumbler gears 24 which are rotatably mounted in the tumbler lever 25. A bolt 26 is provided to secure said tumbler gears 24 in such position that either one of them may be engaged with the feed driven gear 27 which is secured to the feed drive shaft 28. The change gear 29 is secured to the other end of said feed drive shaft 28 and engages with the change gear 30 to drive the feed of the helical cutter as hereinafter described.

80 The index drive shaft 13 which imparts motion directly to the gear blank 6 receives its motion from the main shaft 31, through the worm wheel 32 secured to said index drive shaft and rotated by the worm 33 secured to and rotatable with said main shaft 31. The ratio of the worm wheel 32 and the worm 33 must be equal to or a factor of the ratio between the main drive shaft 31 and the helical cutter, preferably the former, so that for each rotation of the cutter, the 90 index drive shaft will make a complete rotation or a multiple thereof.

85 The main drive shaft 31 is rotated by the cone pulley 34 mounted on a hub 35 of the main frame 1, and is connected to said drive shaft 31 by a flange collar 36 which is carried by the main shaft and cone. A helical cutter 37 is secured in any suitable manner to the cutter shaft 38, mounted to rotate in the swivel carriage 39. The cutter carriage 100 40 on which the swivel carriage 39 is mounted is vertically movable on the stanchion 2, parallel to the axis of the gear blank. The swivel carriage is secured to the cutter carriage in any angular position in relation to 105 the gear blank by means of bolts 41, the heads of which are in a circular T slot 42 arranged in the cutter carriage.

110 The cutter shaft has secured thereto and rotatable therewith a drive gear 43 meshing with the pinion 44, which is secured to the shaft 45 also rotatably mounted in the swivel carriage. On the other end of the pinion shaft 45 a bevel gear 46 is secured engaging with the bevel gear 47 which is secured to a short center shaft 48 about which the swivel carriage 39 pivots. By pivoting the helical cutter about the center shaft 48, a rotatable connection through the bevel gears 47 and 46 is insured in any angular 120 position of the cutter. A bevel gear 49 is secured to the other end of the center shaft 48 and meshes with the bevel gear 50, which is rotatably mounted in the cutter carriage and is slidably keyed to rotate with the vertical cutter drive shaft 51.

125 The cutter drive shaft 51 is mounted in bearings provided in the stanchion 2. A

bevel gear 52 is secured to the lower end 5 of said cutter drive shaft 51 and is arranged to be engaged by either of the reversing bevel gears 53 or 54, which are slidably keyed to the main drive shaft 31 and carried by the yoke or bearing 55. The bevel gears 53 and 54 are for reversing the direction of rotation of the helical cutter, either one of which may be engaged with the vertical shaft bevel gear 52 by the handle 56 which operates the yoke 55. The yoke 55 can be secured to the frame in any position by the bolt 58. The feed of the cutter parallel to the axis of the gear blank is obtained from the index shaft 12 through the tumbler gears hereinbefore described, and the change gears 29 and 30. From this connection it is obvious that the feeding motion of the cutter is dependent on and relative to the rotations of the blank spindle. A change gear 30 is secured to the feed worm shaft 59, having preferably integral therewith, a feed worm 60 which engages with the feed worm wheel 61. A feed screw 62 is mounted in bearings of the main frame and engages a threaded portion 63 of the cutter carriage 40 and is rotated by the feed worm wheel 61, which is secured thereto.

From the construction as described it will be seen that the connections between the cutter and blank spindle are such that a continuous and unvarying motion can be imparted to said cutter and blank spindle. And that in practising this invention it is essential that said cutter and blank spindle are rotated at certain relative speeds and are fed in respect to each other parallel with the axis of the blank spindle in a certain determined ratio, relative to the rotations of the blank spindle. It is immaterial whether the source of power is located as shown in the drawings, or whether it is applied at some other point in the mechanism, so long as the continuous connection between the cutter and blank spindle is maintained.

The procedure to arrange the apparatus to practise the method of cutting helical gears as herein described, is as follows: The gear blank is mounted on, and secured to the work spindle; the cutter secured to the cutter spindle and the swivel carriage adjusted to the proper angle with relation

to the gear and according to the angle of the helices to be cut, and is then secured in such position by the bolts. The feed change gears are secured in accordance with the material of the blank and the angle of the helices. The necessary calculation is then made to obtain the proper index change gears to connect the index driving and index shafts. The change gears so determined are then placed in their proper positions and the machine is ready to operate and will complete the helical gear by one passage of the cutter across the face of the gear blank.

Having described my method of cutting helical gear wheels with a helical cutter, I claim as new and desire to secure by Letters Patent:

1. A method of cutting helical gear wheels, consisting of rotating a gear blank and helical cutter with relative speeds, through a single continuous and unvarying motion from a driver to said gear blank and cutter, respectively, said relative rotations being determined by the ratio of the number of teeth to be cut to the number of threads in the cutter, plus or minus an increment dependent upon the amount of feed desired for each rotation of the gear blank, and imparting a feeding motion substantially parallel to the axis of, and relative to the rotations of, the gear blank, to produce helical teeth on said blank that have a directrix coinciding with the axis of the gear blank.

2. A method of cutting helical gear wheels, consisting of rotating a gear blank and helical cutter with relative speeds, through a single continuous and unvarying motion from a driver to said gear blank and cutter, respectively, said relative rotations being determined by the ratio of the linear pitch of said gear to the lead of said gear plus or minus the amount of feed desired for each rotation of the gear blank, and imparting a feeding motion substantially parallel to the axis, and relative to the rotations of said gear blank, to produce helical teeth on said gear that have a directrix coinciding with the axis of said blank.

WILLIAM F. ZIMMERMANN.
